CASTING MACHINE

Michael H. Kelly, Detroit, Mich., assignor to Kelsey-Hayes Wheel Company, Detroit, Mich., a corporation of Delaware

Application December 26, 1939, Serial No. 310,988

8 Claims. (Cl. 22—65)

The invention relates to casting machines and refers more particularly to machines for casting liners in brake drum shells.

The invention has for an object to provide an improved casting machine having means for heating the shell and means for externally supporting the shell, the heating means being movable into inoperative position and the external supporting means being movable into operative position at the same time.

The invention has for another object to provide improved mechanism for simultaneously moving the heating means and the external supporting means.

The invention has for further objects to provide a simple construction of fluid operated device for moving the heating means and to provide a second fluid operated device for retarding the movement of the heating means during the final portion of its movement to inoperative position.

These and other objects of the invention will become apparent from the following description, taken in connection with the accompanying drawings, in which

Figure 1 is a plan view, partly in section, of a casting unit embodying my invention;

Figure 2 is an end view thereof, partly in section;

Figures 3 and 4 are cross sections on the lines 3—3 and 4—4, respectively, of Figure 1;

Figure 5 is a cross section on the line 5—5 of Figure 4.

The invention, as illustrated, is embodied in a casting unit for centrifugally casting a cast iron liner within the annular flange of a brake drum wrought metal shell. The shell is preferably formed from a flat steel blank by a suitable drawing operation and has the annular flange 1 formed of the generally cylindrical portion 2 and the enlarged generally cylindrical portion 3 terminating in the flared portion 4. The shell has the integral generally radially extending back or web 5 connecting into the opposite edge of the annular flange. The casting unit has the bed 6 provided with the upright bearings 7 spaced from each other. 8 is a hollow shaft journaled in the bearings and having secured to its inner end the pulley 9 and to its outer end the head 10. The pulley is engaged by the belts 11 which are driven by the electric motor 12 suitably supported at one side of the bed 6. 13 are rods extending transversely outwardly from the head 10, the inner ends of the rods being fixedly secured to the head. The rods have fixedly secured to their

outer ends the ring 14 which carries the sealing element 15. The sealing element comprises the annular adaptor plate 16 fixedly secured to the inner side of the ring 14 and the annular sealing member 17 located in a recess in the inner side of the adaptor plate. The sealing ring is formed with the inwardly extending hollow rib 18, the inner or nose portion of which preferably has short parallel sides and the remainder of which has flared sides.

19 is a second hollow shaft axially slidably within and guided by the hollow shaft 8. The second shaft is adapted to be reciprocated by the piston 20 which is reciprocable in the cylinder 21 concentric with the shafts and fixedly secured to the inner side of the pulley 9. A suitable medium under pressure, preferably compressed air, may be admitted to and exhausted from either side of the piston through the pipes 22 and 23 under the control of the valve 26 which is adapted to be manually operated. The valve is of standard construction manufactured by a well known manufacturing concern and receives the medium under pressure from the supply line 24 and pipe 24' and exhausts into the atmosphere through the pipe 25.

The connection between the second shaft 19 and the piston 20 comprises the piston rod 27, the stud 28 threaded into the outer end of the rod 27 and having the integral collar 29 abutting the inner end of the second shaft 19 and the pin 30 which extends through the outer end of the stud and the inner end portion of the second shaft. The arrangement is such that the second shaft is positively reciprocated in both directions and in its outer direction the pin is relieved from shear by the collar upon the stud. A central abutment 31 and a support 32 are fixed upon the outer end of the second shaft 19. The support 32 comprises the body 33 which is sleeved upon and guided by the rods 13 and the ring 34 which is positioned concentrically in the body. The ring 34 is preferably formed with the internal angularly spaced axially extending ribs 35, the internal surfaces together forming an interrupted contour engageable with the external surfaces of the annular portions 2 and 3 and the flared portion 4 of the brake drum annular flange to true, size and externally support the annular flange and also clamp the flared portion against the sealing ring while the molten cast iron is being poured into the shell.

36 is a third shaft which is axially slidably mounted in and guided by the second shaft 19. The third shaft has fixedly secured to its outer

end the pilot abutment 39 and is also provided with the collars 40 and 41 for slidably engaging the second shaft. 42 is a coil spring within the second shaft and located between the stud 28 and the third shaft for yieldably urging the third shaft axially outwardly to engage the collar 40 with the central abutment 31. The pilot abutment is adapted to receive the web 5 of the brake drum shell, the pilot portion being adapted to extend through the central opening in the web and the abutment portion being adapted to abut the adjacent portion of the web.

The brake drum shell is inserted in the machine by passing the shell downwardly between the sealing element and the support 32 until the central opening in its web has registered with the third shaft 38 after which the third shaft is urged inwardly against the resistance of the spring 42 and the shell is located on the pilot abutment. Then the spring is permitted to urge the third shaft axially outwardly to thereby move the shell axially outwardly until the collar 40 abuts the abutment 31. At this time the flared portion 4 of the annular flange of the shell loosely engages the sealing ring 17, the uppermost part of the flared portion resting lightly upon the uppermost part of the rib 18 and the remaining part of the flared portion being spaced sufficiently from the rib to permit the passage of flame therebetween.

46 is a gas burner adapted to be inserted through the opening in the sealing element into the brake drum shell. The burner is carried by the tubular arm 47 which forms a conduit for conducting gaseous mixture to the gas burner and which is rigidly connected to the conduit 48. This latter conduit has a swivel connection with the conduit 49 for supplying the gaseous mixture which comprises gas and air. The conduit 48, the arm 47 thereof, and the burner 46 on the arm and also the conduit 49 are carried by the upright post 50 which is journaled in and supported upon the bracket 51 near one end thereof. The bracket is located at one side of the ring 14. The lower end of the post is provided with the pinion 52 preferably by forming gear teeth integral with the post. The teeth of the pinion mesh with the teeth of the rack 53 preferably formed integral with the piston rod 54 axially reciprocable in the bracket 51. The piston rod is operatively connected at its inner end to the piston 55 which is axially slidabile in the cylinder 56 formed in the inner end of the bracket. 57 is a pipe leading from the inner end of the cylinder 56 to the pipe 22.

The arrangement is such that upon manual operation of the valve 28 to allow compressed air to enter the cylinder 21 and force the piston 20 axially forwardly thereby externally engaging the ring 34 with the annular flange of the brake drum shell, air is at the same time permitted to enter the inner end of the cylinder 56 to move the piston 55 forwardly to thereby swing the gas burner from its operative position within the brake drum shell to inoperative position. In 65 other words, the arrangement provides for simultaneously moving the gas burner to inoperative position and the external support for the annular flange of the brake drum shell to operative position.

To prevent objectionable jarring of the machine during the movement of the gas burner to its retracted or inoperative position by the fluid operated device, comprising the air cylinder 56 and the piston 55, another fluid operated 75

device is used to retard the burner during the final portion of its retractile movement. In detail, 58 is a cylinder mounted on the end of the bracket 51 in axial alignment with the cylinder 56. 59 is a piston within the cylinder 58 and having the reduced end portion 60 adapted to be engaged by the outer end of the piston rod 54. The outer end of the cylinder 58 is connected to the pipe 61 which is in communication at all times with a source of compressed air at the same pressure as the compressed air in the pipe 57. The two cylinders 56 and 58 are preferably of the same diameter. The arrangement is such that when compressed air is admitted to the cylinder 56 and its piston and piston rod are advanced, the rod during the final portion of its advancement engages the reduced end portion 60 of the piston 59, which latter then yieldably retards further advancement, the parts finally coming to rest in a position determined by the balance in air pressures in the two cylinders.

61 is a ladle adapted to contain molten iron. The ladle is mounted upon the arm 62 which is fixed upon the horizontal shaft 63 journaled in the free end of the arm 64. The latter arm is pivotally mounted upon the bracket 65 to swing through a horizontal path. 66 is a handle upon the shaft 63 for swinging the ladle from inoperative position outside the brake drum shell to operative position inside the shell and then tilting the ladle to pour the molten iron against the annular flange of the shell.

What I claim as my invention is:

1. In a casting machine, the combination with means for rotatably supporting an annular member, of a gas burner insertable within the annular member for heating the same, other means engageable with the external surface of the annular member for rotatably supporting the same, means for simultaneously moving said gas burner from within the annular member and for moving said other means into engagement with the annular member, and means for pouring fluid material into the annular member when heated and supported.

2. In a casting machine, the combination with means for rotatably supporting an annular member, of means insertable within the annular member for heating the same, means externally engageable with the annular member to rotatably support the same, fluid operated devices operatively connected to said heating means and externally engageable means for respectively moving said heating means away from the annular member to inoperative position and said externally engageable means to operative position in external engagement with the annular member, common means for controlling said fluid operated devices, and means for pouring fluid material into the annular member after having been heated and while externally supported.

3. In a machine for casting a liner in the annular flange of a wrought metal brake drum shell, the combination with a sealing element engageable with the free edge portion of the annular flange, of means for urging the shell toward said sealing element, said sealing element and urging means serving to rotatably support the shell, a gas burner insertable within the shell for heating the annular flange, an external support movable into engagement with the annular flange and adapted to clamp the free edge portion against said sealing element, said exter-

nal support and sealing element serving to rotatably support the shell, fluid operated means operatively connected to said gas burner and external support for simultaneously moving said gas burner from within the shell to inoperative position and said external support into engagement with the annular flange, and means for subsequently pouring liner material into and against the annular flange.

4. In a machine for casting a liner in an annular portion of a shell, the combination with means for rotatably supporting the shell, of means insertable within the shell for heating the annular portion, means engageable with the external surface of the annular flange for rotatably supporting the same, means for simultaneously withdrawing said heating means from within the shell and moving said supporting means into engagement with the annular flange, and means insertable within the shell for pouring fluid liner material into the annular flange after having been heated and while externally supported.

5. In a casting machine, the combination with means for rotatably supporting an annular member, of a gas burner insertable within the annular member for heating the same, a movable member carrying said burner, a fluid operated device operatively connected to said movable member for moving the same in one direction, and a second fluid operated device opposing said first mentioned device and serving to retard said movable member during the final portion of its movement.

6. In a casting machine, the combination with

means for rotatably supporting an annular member, of a gas burner insertable within the annular member for heating the same, a pivotal arm carrying said burner, a member revoluble about its axis for supporting said arm, a pair of axially spaced cylinders having ports in their outer ends for the passage of a medium under pressure, pistons within said cylinders movable toward each other under pressure of the medium, and a rod connected to one of said pistons and operatively connected to said revoluble member and adapted to engage the other of said pistons.

7. In a casting machine, the combination with means for rotatably supporting a member, of movable heating means for the member, other means movable into engagement with the member for holding the same to size, said other means providing for rotatably supporting the member, means for moving said heating means away from the member to inoperative position and said other means to operative position in engagement with the member at the same time, and means for pouring fluid casting material against the member while heated and while said other means is in operative position.

8. In a casting machine, the combination with means for rotatably supporting a member, of movable heating means for the member, a fluid operated device operatively connected to said heating means for moving the same in one direction, and a second fluid operated device opposing said first mentioned device and serving to retard said heating means during its movement.
